UNITED STATES PATENT OFFICE

JOSEPH W. BRUNETTE, OF FORDSON, MICHIGAN

SYRINGE ATTACHMENT

Application filed March 2, 1929. Serial No. 343,975.

This invention appertains to improvements in the broad class of surgery and more specifically the invention aims to provide an attachment for syringes of the douching type, which may be utilized as a shield to regulate penetration of the syringe and in the capacity of a drain for permitting the douching fluid to escape from the vagina.

An important object of the invention is to provide an attachment of this character which can be readily removed from a syringe to permit cleaning thereof.

Another paramount object of the invention is to provide an attachment for syringes, whereby the douching fluid may be effectively controlled in its application to the subject under treatment.

Another object is to provide an attachment in the nature of a shield of such brief construction as to permit its manufacture at nominal cost.

These and other objects of the invention will become more apparent to the reader after considering the invention as described and claimed hereinafter.

In the drawings:—

Figure 1 represents a sectional view through the improved attachment.

Fig. 2 represents an elevation of the outer side of the attachment.

Referring to the drawings, wherein like numerals designate like parts, the novel device includes a body 3 concaved at one side and provided with a tapering protuberance 4 projecting from the intermediate portion of the same side. An opening 5 extends through the central portion of the plate 3 and is enlarged within the protuberance 4 to provide a relatively large chamber 6.

40 A plurality of orifices 7 are formed in the wall of the protuberance 4 to provide inlets for the fluid returning after its application to the subject.

45 A duct 8 extends from the chamber 6 and opens at the outer side 9 of the plate, and is adapted to receive the ribbed end portion 10 of a nipple 11. The nipple 11 serves to receive a drain tube 12.

50 In dotted lines in Fig. 1, a conventional nozzle 13 is shown disposed through the open-

ing 5 and the chamber 6 for delivering the douching fluid to the point within the vagina desired.

While the body 9 is preferably constructed of some resilient material such as rubber, it is to be understood that no restriction is to be placed on the material, and that certain changes may be made in the specific shape and size of the device without departing from the spirit and scope of the invention as claimed hereinafter.

Having thus described my invention, what I claim as new is:—

55 A shield for a syringe comprising a substantially solid body of resilient material having a flat base of substantial thickness concaved on its upper side, and a tapering protuberance extending centrally from the concaved side of the base, said body having an opening extending centrally through the base and protuberance for the reception of a syringe nozzle and having the opening restricted at the lower portion of the body to dispose the material of the latter closely about the nozzle for substantially the full thickness of the base and being enlarged at the upper portion of the body to provide a relatively large waste collecting chamber around the nozzle, said body being further provided with end flow openings communicating with the chamber through the side walls of the protuberance and a drain opening communicating with the chamber from the bottom side of the base.

70 75 80 85 In testimony whereof I affix my signature. JOSEPH W. BRUNETTE.
